(57) **CLAIM**

The ornamental design for a display screen or portion thereof with graphical user interface associated with insulin delivery, as shown and described.

DESCRIPTION

FIG. 1 is a front, overall view of a display screen or portion thereof showing a first embodiment of the design, and FIGS. 2-5 are enlarged views of portions of the design of FIG. 1 and are identified in FIG. 1.

FIG. 2 is a front view of an enlarged first image defining a portion of the display screen or portion thereof of FIG. 1. FIG. 3 is a front view of an enlarged second image defining a portion of the display screen or portion thereof of FIG. 1. FIG. 4 is a front view of an enlarged third image defining a portion of the display screen or portion thereof of FIG. 1. FIG. 5 is a front view of an enlarged fourth image of the display screen or portion thereof of FIG. 1.

FIG. 6 is a front, overall view of a display screen or portion thereof showing a second embodiment of the design, and FIGS. 7-11 are enlarged views of portions of the design of FIG. 6 and are identified in FIG. 6.

FIG. 7 is a front view of an enlarged first image defining a portion of the display screen or portion thereof of FIG. 6. FIG. 8 is a front view of an enlarged second image defining a portion of the display screen or portion thereof of FIG. 6. FIG. 9 is a front view of an enlarged third image defining a portion of the display screen or portion thereof of FIG. 6. FIG. 10 is a front view of an enlarged fourth image of the display screen or portion thereof of FIG. 6; and,

FIG. 11 is a front view of an enlarged fifth image of the display screen or portion thereof of FIG. 6.

The broken line showing of a display screen with graphical user interface is included for the purpose of showing portions of the article which form no part of the claim.
